CHRISTMAS TREE HOLDER

Filed Dec. 12, 1927

Inventor:
John Gabel
By Arthur F. Durand
Gtoy.

UNITED STATES PATENT OFFICE

JOHN GABEL, OF CHICAGO, ILLINOIS

CHRISTMAS-TREE HOLDER

Application filed December 12, 1927. Serial No. 239,285.

This invention relates to supports for Christmas trees or things of a similar character.

Generally stated, the object of the invention is to provide a novel and improved construction whereby a Christmas tree or similar object can be supported on the floor, in an upright position, in a more satisfactory manner than heretofore.

10 It is also an object to provide a support which is adjustable for trees or other objects of different sizes.

Another object is to provide a base for the support, having improved means for holding 15 water to keep the tree from getting dry.

It is also an object to provide certain details and features of construction and combinations tending to increase the general efficiency and the desirability of a support of 20 this particular character.

To these and other useful ends, the invention consists in the matters hereinafter set forth and claimed, and shown in the accompanying drawings, in which—

25 Fig. 1 is a vertical section of a support embodying the principles of the invention.

Fig. 2 is a plan of the said support, certain portions being broken away in both views for convenience of illustration.

30 As thus illustrated, the invention comprises a horizontally disposed and rectangular frame comprising the bars 1 that are bent outwardly at their ends and held together by the bolts 2 as shown. The bars 3 have their outer ends held between the end portions of the bars 1, so that they are held in place by the said bolts 2, while the inner ends of the bars 3 are held in place by bolts 4 inserted through the lugs 5 on the sheet metal base

35 plate 6 as shown, which plate 6 or other suitable element forms a necessary link in a separable frame structure. A sheet metal cup 40 7, preferably formed to taper downwardly, is secured to the plate 6 in any suitable or desired manner. The four clamping members 8 are adjustably held together by the bolts 9, as shown in Fig. 2 of the drawings, and upwardly extending inclined bars 10 have their upper ends held in place by these 45 bolts 9, while the lower ends of the bars 10

are inserted between the ends of the bars 1 and held in place by the bolts 2 previously mentioned.

With the foregoing construction, which is illustrative of one form of the invention, the 55 trunk 11 of the tree can be inserted in place as shown, the clamping elements 8 being adjustable to clamp tree trunks of different diameters. The lower end of the tree trunk will rest in the cup 7, as shown, and the tree 60 will thus be kept from drying out by the water held in said cup.

By removing the bolts 2 and 9, the entire structure can be knocked down, it will be seen, and conveniently stored, or packed for transportation. By means of said bolts the framework of the support can thereafter be quickly assembled and held together for use in the manner shown and described.

It will be understood, of course, that the 70 invention is not limited to Christmas trees, as it may be used for other purposes, as for supporting flag poles or signs or anything else having a lower portion that may be clamped in place instead of the tree trunk.

It will be seen that each end of every bar 75 1, 3 and 10, is disconnectable, whereby the entire structure may be taken apart for storage or shipment. The bars 1 form a rectangular base for the frame, and the cup 7 is at 80 the center of the base, and the cup support 6 rests on the floor to take the weight of the tree or other object off the frame bars. Thus no weight is imposed upon the frame bars by the tree or other object, and with the four 85 equidistant corners of the rectangular base of the frame bearing upon the floor, the entire supporting structure is braced in all directions against tipping over.

Without disclaiming anything, and without prejudice to any novelty disclosed, what I claim as my invention is:

1. A support for engaging and holding upright the trunk portion of a Christmas tree or any other object having a portion similar 95 to the tree trunk, comprising bars forming a frame provided at its top with engaging means to hold the tree trunk or other object in position, and having a structurally separate center member at the bottom of said 100

frame to engage the lower end of said tree trunk or other object, forming a link in the frame and resting on the floor, said frame having a horizontal rectangular base of some breadth to rest horizontally on the floor, the four corners of the base being spaced in fixed relation by the four sides of the rectangle, and the frame tapering upward at a fixed angle from the four corners of said base to said engaging means.

10 2. A structure as specified in claim 1, said frame comprising bars detachably held together by removable bolts, there being a removable bolt at each end of each bar, some of said bars detachably connected to said upper engaging means, and some of said bars being detachably connected to said member, each end of every bar being disconnectable whereby the support may be taken apart and knocked down for storage or transportation.

15 3. A structure as specified in claim 1, said lower member being in the form of a downwardly tapered cup to receive the lower end portion of the tree trunk or other object, disposed at the center of said rectangular base to rest on the floor to take the weight of the tree or other object off said frame adapted to contain water to keep the trunk moist.

20 4. A structure as specified in claim 1, said upper engaging means being adjustable in diameter for tree trunks or other objects of different diameters.

Specification signed this 9th day of December, 1927.

JOHN GABEL.
